GEORGE H. HAMILTON, OF EAST GRAND RAPIDS, MICHIGAN, ASSIGNOR TO AMERICAN
HEATING COMPANY, OF GRAND RAPIDS, MICHIGAN, A CORPORATION OF NEW
JERSEY

SUPPORT FOR BOOKS AND THE LIKE

Application filed March 9, 1931. Serial No. 521,132.

The present invention relates to supports for books and the like; and its object is, generally, to provide an improved device of that character adapted to be mounted in a school 5 desk or on a table or other suitable base; and more particularly, to provide such a device having parts of improved construction and cooperation, relatively movable to the device's position of use and to a collapsed position 10 when the device is not in use.

This and any other and more specific objects hereinafter appearing are attained by, and the invention finds preferable embodiment in, the illustrative structure particularly 15 described in the body of this specification and illustrated by the accompanying drawings, in which:

Figure 1 is a top plan view of a desk top (partially broken away) and a support for 20 books and the like applied thereto, said device being shown in collapsed position;

Figure 2 is a transverse vertical sectional view thereof taken on line 2—2 of Figure 1; said support being shown in dotted lines in 25 its raised or usable position;

Figure 3 is a horizontal sectional view of parts of the same taken on line 3—3 of Figure 2;

Figure 4 is a vertical sectional view of parts 30 of the same taken on line 4—4 of Figure 2; and

Figure 5 is a top plan view of said support (partially broken away) and of parts of the desk top.

In these drawings a support for books and the like is shown mounted in a box-like desk top 1 such as (with suitable legs) is used in schools, etc. As illustrated, this desk top has a bottom 2, end walls 3, front wall 4, rear wall 5 and a cover comprising a fixed portion 6 and a swingable closure portion 7 united by hinges 8.

The book supporting device comprises a supporting member 9 vertically slidable in the desk top, said member's oppositely extending lugs or pins 10 bearing in the vertical grooves 11 in the end walls 12, of a casing 30 having a front wall 13 and a rear wall which is the rear wall 5 of the desk top, said end walls 12, and front wall 13 extending be-

tween the desk top's bottom 2 and the cover's fixed portion 6 and assisting to support said portion by said bottom.

This supporting member 9 is preferably a wooden board of considerable thickness, 55 grooves 14 being formed in its opposite sides. Slidably bearing on said opposite sides are metal plates 16, 17 having inwardly turned ribs 18 slidably bearing in the grooves 14, these plates being connected by bars or bolts 60 19 extending through a slot 20 in the supporting member 9. The upper end portions 21, 22 of these metal plates 16, 17 respectively are turned outwardly at right angles, the end portion of plate 16 carrying, as by suitable attaching rivets 23, the body member 24 of the book rest, designated generally 25, and being turned upwardly over said body member's free forward edge to form a ledge 26 on which the bottom edge of the book, etc. 65 70 on the book rest abuts. The upper end portion 22 of the other plate 17 is also fastened as by rivets 27 to body member 24.

The extension member 28 of the book rest carries as by rivets 34 the other leaf 35 of a hinge connecting by the pintle 29 the two members of the book rest. The supporting member 9 and the plates 16, 17 thus form a collapsible leg for the book rest, whereby 75 said plates and supporting member in their vertical positions may be relatively moved downwardly into the casing 30 when the device is not in use, thus occupying the position shown in solid lines in Figure 2, and the extension portion 28 of the book rest may be turned 80 85 downwardly as shown in that view, so that the two portions 24 and 28 of the book rest approximately fill the gap 31 between the spaced parts of the fixed portion 6 of the desk top's cover.

When the supporting member 9 is slid to the position shown in dotted lines in Figure 2, it may be tilted forwardly, as thus shown, its lugs 10 turning in the grooves 11 and the lower end portion 32 of said member engaging the inturned upper flange 33 of the desk top's rear wall to hold the device in the forwardly tilted position of use shown in said dotted lines.

The invention being intended to be pointed 100

out in the claims, is not to be limited to or by details of construction of the particular embodiment thereof illustrated by the drawings or hereinbefore described.

5. I claim:

1. In a device of the character described: a book rest; a support therefor comprising a middle member having vertical grooves in its opposite sides; a pair of members on the opposite sides respectively of the middle member, secured at their upper ends to the book rest and having vertically extending ribs slidably bearing in the grooves.

10. 2. In a device of the character described: a book rest; a support therefor comprising a middle member having a vertical slot therethrough and vertical grooves in its opposite sides; a pair of members on the opposite sides respectively of the middle member, secured at their upper ends to the book rest, connected by a bar extending through said slot, and having vertically extending ribs slidably bearing in the grooves.

15. 3. In a device of the character described: a book rest; a support therefor comprising a middle member having vertical grooves in its opposite sides; a pair of members on the opposite sides respectively of the middle member, having outwardly turned upper end portions secured to the book rest, and having vertically extending ribs slidably bearing in the grooves.

20. 4. In a device of the character described: a book rest comprising a body portion and an extension connected thereto by a hinge having leaves one of which is mounted on said extension; a support for the book rest comprising a middle member having vertical grooves in its opposite sides; a pair of members on the opposite sides respectively of the middle member, one of said pair having an outwardly turned upper end portion secured to said body portion and the other one of said pair having an outwardly turned upper end portion secured to said body portion and forming the other leaf of said hinge, said pair of members having vertically extending ribs slidably bearing in the grooves.

25. 5. In a device of the character described: a book rest comprising a body portion and an extension connected thereto by a hinge having leaves one of which is mounted on said extension; a support for the book rest comprising a middle member having vertical grooves in its opposite sides; a pair of members on the opposite sides respectively of the middle member, one of said pair having an outwardly turned upper end portion secured to said body portion and extending around one edge thereof to form a book-supporting ledge, and the other one of said pair having an outwardly turned upper end portion secured to said body portion and forming the other leaf of said hinge, said pair of mem-

bers having vertically extending ribs slidably bearing in the grooves.

6. In a device of the character described: a book rest comprising a body portion and an extension connected thereto by a hinge having leaves one of which is mounted on said extension; a support for the book rest comprising a broad flat middle member having spaced vertical grooves in each of its opposite sides; a pair of sheet metal members on the opposite sides respectively of the middle member, one of said pair having an outwardly bent upper end portion secured to said body portion and the other one of said pair having an outwardly bent upper end portion secured to said body portion and forming the other leaf of said hinge, said pair of members having inwardly bent vertically extending rib portions slidably bearing in the grooves.

7. In combination with a box-like desk top containing vertically extending slide bearings; a book rest; a support therefor comprising a broad flat member having a vertical movement in said bearings and provided with vertical grooves in its opposite sides; a pair of sheet metal members on the opposite sides respectively of the middle member, secured at their upper ends to the book rest, and having inwardly bent vertically extending rib portions slidably bearing in the grooves.

8. In combination with a box-like desk top containing vertically extending slide bearings; a book rest; a support therefor comprising a broad flat member having a vertical movement in said bearings and a forwardly tilting movement in its raised position, and provided with vertical grooves in its opposite sides; a pair of sheet metal members on the opposite sides respectively of the middle member, secured at their upper ends to the book rest, and having inwardly bent vertically extending rib portions slidably bearing in the grooves.

In testimony whereof I have hereunto set my hand at Grand Rapids, Michigan, this 5th day of March, 1931.

GEORGE H. HAMILTON.
